[57] CLAIM

The ornamental design for a door chest, as shown and described.

DESCRIPTION

FIG. 1 is a perspective view of a door chest, showing my new design;

FIG. 2 is a front elevational view thereof;

FIG. 3 is a right side elevation thereof, the left side elevation being a mirror image; and,

FIG. 4 is a top plan view thereof.

The rear side and the bottom of the chest are plain and unadorned.
